CONCEALED ELONGATING HINGE

Delbert J. Rea, Detroit, Mich.

Application November 9, 1938, Serial No. 239,727

3 Claims. (Cl. 16—164)

The invention relates to improvements in concealed elongating hinges and the primary object is to provide a hinge having improved elongating or throw-out lever connections with the hinge butts.

Another object of the invention resides in the provision of a concealed elongating hinge for hanging closures, such as automobile doors, the hinge being so constructed that the initial opening swing of the closure will occur about a single pintle to permit clearance of the closure relative to its frame or jamb, after which the elongating or throw-out movement will take place about a plurality of pintles.

15 A further object of the invention is to provide a hinge having elongating or throw-out lever connections with the hinge butts and which connections are each pivotally secured to one hinge butt and slidably in a curvilinear path thru an opening extending transversely of the other hinge butt.

20 A still further object is to provide a hinge of the character described having lever connections slidable in curvilinear paths thru openings transversely of the hinge butts, the lever connections having opposite faces so tapered as to constantly engage the walls bounding said transverse openings during various stages of movement of the lever connections along said curvilinear paths.

25 Other objects and advantages of the invention will become apparent during the following detailed description, taken in connection with the accompanying drawing, forming a part of this specification, and in which drawing:

30 Figure 1 is a perspective view of a hinge embodying my invention, the parts being illustrated in closed relationship.

35 Figure 2 is a view, partly in top plan and partly in horizontal section, of the hinge, and showing its application to a closure, the parts being in their closed relation.

40 Figure 3 is a vertical sectional view taken substantially on the line 3—3 of Figure 2.

45 Figure 4 is a horizontal sectional view, showing in full lines, the relationship of parts, at a stage intermediate the initial non-elongating movement and the offset or throw-out movement, and in broken lines illustrating the relationship of parts during a stage of said offset or throw-out movement.

50 In the drawing, which for the purpose of illustration shows only a preferred embodiment of the invention, and wherein similar reference characters denote corresponding parts throughout the

views, the letter A generally designates the hinge, B a closure frame, and C a closure.

Referring to the hinge A, the same comprises a pair of butts 10—11 provided with openings 12 for securing the butts, as by screws 13, to the closure C and frame B. In the example shown, the butt 10 is secured to the frame B and the butt 11 is fixed to the closure C. Projecting from the inner faces of the butts 10—11, at the pivotal ends thereof, are spaced-apart knuckles 14—15, 10 respectively, the free end portions of the butts 10—11 being provided with transverse openings 16—17, respectively, of rectangular shape. The walls bounding the openings 16—17 form edges 18—19 and 20—21, respectively, at diagonally opposite extremities of the openings, the edge 21 of the opening 17 constituting the outer end of a tooth 22 defined by an oblique face or wall 23 of the opening 17.

20 Connecting the butts 10—11 for swinging movement relative to one another is a plurality of crossed levers 24—25, each comprising a link end portion 26 and an angularly disposed shank end portion 27 having tapering or convergent opposite faces 28—29. In the example shown, two 25 levers 24 are disposed in spaced relation with a single lever 25 interposed therebetween, the combined areas of given cross-sections of the levers 24 being substantially equivalent to the area of a corresponding cross-section of the lever 25. 30

25 Pivottally securing the levers in crossed relation intermediate their shank and link end portions is a pintle 30. At their link end portions the levers 24—25 are pivotally secured to the knuckles 15—14, respectively, as by pintles 31, the shank 35 end portions of the levers 24—25 being slidably disposed in the openings 16—17 respectively. The lever 25 is reduced along its shank end portion as by forming a notch 32 in the face 28, this notch being defined by an arcuate wall 33 having 40 a radius R substantially equal to the distance between the pintle 31 carried by the knuckle 15 and the edge 21 of the tooth 22, and conforming to the pivotal swinging movement of the tooth 22 about the pintle, whereby the notch 32 may 45 accommodate the tooth 22 between predetermined stages of angular swinging movement of the butt 11.

30 From an inspection of the drawing, it will be seen that the shank end portions 27 are so tapered toward their free ends as to remain in constant contact, at their opposite faces 28—29, with the respective edges 18—19 and 20—21, during all stages of angular swinging movement of the butts 10—11, with the exception of those stages of 55

angular swinging movement of the butt 11, in which the tooth 22 is partially or wholly disposed within the notch 32. In other words, the sections of the shank end portions 27 included between the edges 18-19 and 20-21, as formed by the intersections of the planes P, are of constant dimensions substantially equaling that of the distance between said edges, due to the fact that the variable angular position of the shank end portions relative to the openings 16-17 during movement of the shank end portions in curvilinear paths as governed by the pintles 30-31 is compensated by the variable cross-sectional width of said shank end portions disposed in said openings during various stages of movement of the shank end portions along said curvilinear paths, except that those sections, such as that formed by the intersection of the plane P', between the edges 20-21, during stages of movement of the lever 25 at one end portion of its curvilinear path, have dimensions less than that of the distance between said edges 20-21, whereby the butt 11 may independently swing about its pintle 31 for a predetermined distance at the beginning of its opening movement and at the end of its closing movement.

In swinging the closure C to an open position, the butt 11 will first swing from the position shown in Figure 2 to that illustrated in Figure 30 4 without affecting the relative positioning of the remaining parts of the hinge, and without any offset or elongating action, whereby the closure C may clear the closure frame B. Then, as shown in Figure 4, the edges 20-21 of the butt 11 slidably contact the faces 28-29 of the lever shank in a manner whereby further opening movement of the hinge will bring about the desired elongating or throw-out action between the pivoted link end portions and the sliding shank end portions 35 connecting the butts. On the return swing of the closure C, the edge 21 slidably forces the levers 24-25 into their normal closed positions, at which time the edge 21 is disposed adjacent the entrance of the notch 32, thus allowing the butt 11 to complete its final closing movement, without affecting the remaining parts of the hinge, this final movement being the same as the action of a single pintle hinge, whereby the closure may swing into its frame without requiring more than 40 the usual angle or bevel therein.

Various changes may be made in the form of the invention herein shown and described, without departing from the spirit of the invention, or the scope of the following claims.

55 I claim:

1. A hinge construction comprising a pair of butts having openings transversely therethrough, said openings being defined at opposite sides of said butts by edges, a plurality of levers each including a link end portion and a shank end portion, means pivotally connecting said levers in crossed relation intermediate their end portions, means pivotally connecting said levers at their

link end portions each to one of said butts, said shank end portions including convergent faces contacting said edges at opposite sides of said butts, said shank end portions being movable in curvilinear paths as governed by said pivot means to vary the angular and axial relationship of said shank end portions to said openings, the sections included between said edges during various stages of movement of said shank end portions relative to said openings having a constant 10 dimension substantially equaling that of the distance between said edges. 5

2. A hinge construction comprising a pair of butts having openings transversely therethrough, said openings being defined at opposite sides of 15 said butts by edges, a plurality of levers each including a link end portion and a shank end portion, means pivotally connecting said levers in crossed relation intermediate their end portions, means pivotally connecting said levers at their 20 link end portions each to one of said butts, said shank end portions including convergent faces contacting said edges at opposite sides of said butts, said shank end portions being movable in curvilinear paths as governed by said pivot means 25 to vary the angular and axial relationship of said shank end portions to said openings, the sections included between said edges during various stages of movement of said shank end portions relative to said openings having a constant 30 dimension substantially equaling that of the distance between said edges, a given one of said shank end portions being provided with a reduced portion receiving one of said edges, whereby those sections included between the edges contiguous to the given shank end portion during stages of movement at one end of the curvilinear path of the given shank end portion have dimensions less than that of the distance between said 35 edges. 40

3. A hinge construction comprising a pair of butts including cam walls defining openings extending transversely through said butts, a given one of said butts including a cam wall formed with a tooth, a plurality of levers each including 45 a link end portion and a shank end portion, means pivotally connecting said levers in crossed relation intermediate their end portions, means pivotally connecting said levers at their link end portions each to one of said butts, said shank end 50 portions including convergent faces each slidably contacting the cam walls of one of said openings whereby said shank end portions, upon relative swinging movement of said butts, are moved along curvilinear paths transversely of 55 said butts, one of said shank end portions being provided in one of its convergent faces with a notch for the accommodation of said tooth, said notch being defined by an arcuate wall conforming to the arcuate movement of said tooth 60 about the pivotal axis of said given butt. 55
